FIG. 8.

INVENTOR
JOHN H. STONE
By *Clarence S. Walker*,
ATTORNEY

UNITED STATES PATENT OFFICE.

JOHN H. STONE, OF BUFFALO, NEW YORK.

AWNNG FASTENER.

Application filed January 3, 1922. Serial No. 526,802.

To all whom it may concern:

Be it known that I, JOHN H. STONE, a citizen of the United States, residing at Buffalo, in the county of Erie and State 5 of New York, have invented certain new and useful Improvements in Awning Fasteners, of which the following is a specification.

This invention relates to an improvement 10 in an awning fastener and more particularly to such a fastener composed of two parts, one of which is adjustably secured to the awning while the other is rigidly fixed to the wall of the building on which 15 the awning is to be installed.

It is customary to secure an awning to the building by means of screw eyes screwed into the window frame or other part of the building and passing through grommets 20 fixed at regular intervals along the rear edge of the awning. When the awning is taken down in the fall it is of course necessary to unscrew each of the screw eyes and when the awning is put up in the spring the screw 25 eyes are screwed into the same holes as before. Obviously after this has been done several times the screw eyes will no longer hold in the wood. Hence it will be necessary either to employ screw eyes having a 30 thicker shank or else to change the position of the awning on the window frame and make a new set of screw holes. After several of such shifts that portion of the window frame will be honeycombed with holes 35 so that, not only is the appearance of the building spoiled but also it is practically impossible to install an awning on that frame. Moreover, when a new awning is installed the grommets on it are never located 40 in exactly the same positions as the grommets on the old awning so that new holes must be made for some, at least, of the screw eyes.

One object of this invention is to avoid 45 this defacement of the building and the impossibility of reinserting screw eyes in the same holes by providing a multi-part fastener, one part of which is rigidly secured to the building and need not be removed when 50 the awning is put up or taken down while the other part is carried on the awning.

Another object is to provide a clamp for holding the rear edge of the awning firmly without marking it, which clamp can be adjusted along the edge of the awning so 55 that it can be brought into coincidence with the part of the fastener already fixed to the building.

A further object is to provide at the rear edge of an awning a stiffening rod or bar 60 with which such clamp co-operates so that the entire rear edge is held at a fixed distance from the building when the awning is installed, thus eliminating the sags and gaps that exist when the awning is supported at intervals through grommets along the rear edge in the usual manner.

A still further object is to provide awning fasteners to which the pulley blocks 70 used to support the awning cords are secured.

Other objects will appear from an examination of the following description in connection with the accompanying drawings 75 which form a part thereof and in which

Fig. 1 is a view of the rear edge of an awning equipped with a fastener embodying this invention;

Fig. 2 is a sectional view taken along the line 2—2 of Fig. 1 disclosing one form of 80 this invention;

Figs. 3 and 4 are cross sectional views taken on the lines 3—3 and 4—4 of Fig. 2;

Fig. 5 is a sectional view similar to Fig. 2 showing a second embodiment of this in- 85

vention;

Figs. 6 and 7 are cross sectional views taken on the lines 6—6 and 7—7 of Fig. 5;

Fig. 8 is a sectional view similar to Figs. 2 and 5 showing a third embodiment of this 90

invention;

Fig. 9 is a cross sectional view taken on the line 9—9 of Fig. 8; and

Fig. 10 is a cross sectional view similar to Fig. 9 showing a fourth embodiment of 95

this invention.

Referring to the drawings the reference numeral 20 is used to designate an awning mounted on a building 21 by fasteners embodying this invention. The rear edge of the awning 20 is folded under to form a hem 22 into which is inserted a stiffening rod 23

usually of a length substantially equal to the width of the awning.

The fasteners 24 are made up of two parts of which one, 25, is a clamp carried 5 by the awning while the other, 26, is a bracket secured to the building by screws 27 or other suitable means. The clamp 25 is hooked over the rod 23 and the hem 22 and may be slid along the edge of the awning until the proper position is reached. Obviously by reason of the relative sizes of 10 rod and clamp the awning can not pull out of engagement.

In the first embodiment, illustrated in 15 Figs. 1, 2, 3, and 4, part of the clamp 25 behind the awning is slotted to form a tongue 28 and side strips 29 provided at the lower ends with eyes 30. The tongue 28 is somewhat offset relative to the strips 20 29 and is provided with a transverse hill or bump 31 for a reason to be pointed out later. The bracket 26 has a raised section 32 intermediate the ends 33 which are firmly secured to the building 21 by screws 27. 25 Thus there is formed a pocket into which the tongue 28 is inserted when the awning is put up. The hill or bump 31 projects below the section 32 and helps to hold the tongue in place. (See Fig. 2.) Moreover 30 it will appear from an inspection of Figs. 2 and 3 and 4 that the section 32 of the bracket is gripped between the tongue 28 and strips 29 so as to practically eliminate any rattle due to looseness of the awning 35 mountings.

The second embodiment is intended for use where the awning is mounted on a building just under a cornice or other projection 34 which prevents inserting the 40 clamps into the brackets from above as in the first embodiment. In place of the bracket used in the first embodiment which was fastened at each end to the building there is employed a bracket 26' secured at 45 one end only, 35, to the building, the other end 36 being spaced from and parallel to the building. A heel 37 may be formed on the end 36 as shown in Fig. 6 thus making a pocket for the clamp. The clamp 25' 50 used in this embodiment differs from the one used in the first embodiment chiefly in the fact that instead of forming a tongue 28 the back plate is slotted and the portion 38 between the slots is depressed so that 55 the clamp can be slipped longitudinally on to the end 36 of the bracket. The heel 37 will, of course, engage the rear edge of the portion 38 and hold the clamp in position. The lower end of the clamp is 60 provided with a slot 39 to take the place of the eyes 30 in the first embodiment.

The embodiment shown in Figs. 8 and 9 is intended to be used in place of the first embodiment for supporting smaller, lighter 65 awnings. The clamp 40 of this third em-

bodiment is narrower than the clamp 25 so that instead of forming a tongue in the back plate, the back plate acts as a tongue itself and is inserted behind the portion 32 of the bracket 26 which is the same as 70 that used in the first embodiment.

The fourth embodiment shown in Fig. 10 is an adaptation of the third embodiment for use under a cornice or other projection and consists in the substitution of a two 75 plane bracket 41 for the bracket 26' of the third embodiment. The bracket 41 is the same in all essential points as the bracket of the second embodiment and differs therefrom only by the omission of the heel 37. The clamp 40 is the same in each case 80 so that an awning equipped with that clamp can be used with equal facility in conjunction with either of these brackets illustrated. This is equally true of the clamp 85 25 but the clamp 25' can only be used with the brackets 26' and 41.

The eyes 30 in the clamp 25 and the slot 39 in the clamp 25' are formed to receive the pulley blocks 42 by which the awning cords are carried. Thus the complete awning assembly is independent of the brackets and of the building on which the awning is installed which is a great advantage over 90 the common practice of hooking the pulley blocks onto the awning holding screw eyes.

While certain embodiments have been shown and described I am not to be limited thereby since it is obvious that others may be made without departing from the spirit 100 and scope of my invention set forth in the following claims.

Having thus described my invention that which I claim as new and for which I desire protection by Letters Patent of the 105 United States is the following:

1. An awning fastener comprising a clamp mounted upon and adjustable along the rear edge of the awning, said clamp having a tongue, a strip at each side thereof, and an eye at the tip of each strip, and a bracket having a pocket into which said tongue is inserted when the awning is installed.

2. An awning fastener comprising a bracket secured to the casing of the opening to be protected by the awning, said bracket having a horizontal portion offset from the body of the bracket, a clamp having a portion extending over the top, front and part of the bottom of the head rod of said awning, a tongue adapted to be inserted behind the offset portion of said bracket, and eye provided means at each side of said tongue, between which means and said portion the awning is held below said head rod.

3. An awning fastener comprising a bracket secured to the casing of the opening to be protected by the awning, said

bracket having a horizontal portion offset from the body of the bracket, a clamp having a portion extending over the top, front and part of the bottom of the head rod 5 of said awning, a tongue adapted to be inserted behind the offset portion of said bracket, one of said elements having a trans- verse heel by which they are held in position, and eye provided means at each side of said tongue, between which means and 10 said portion the awning is held below said head rod.

In testimony whereof I affix my signature.

JOHN H. STONE.
